UNITED STATES PATENT OFFICE.

GEORGE W. LANCASTER, OF RICHMOND, VIRGINIA, ASSIGNOR TO UNIVERSAL SCREEN & BLIND COMPANY, INCORPORATED, A CHARTERED COMPANY.

WINDOW-SHUTTER-CLOSING DEVICE.

1,081,842.

Specification of Letters Patent. Patented Dec. 16, 1913.

Application filed March 17, 1913. Serial No. 755,000.

To all whom it may concern:

Be it known that I, GEORGE W. LANCASTER, citizen of the United States, residing at Richmond, in the county of Henrico and State of Virginia, have invented certain new and useful Improvements in Window-Shutter-Closing Devices; and I do hereby declare the following to be a full, clear, and exact description of the invention, such as will 10 enable others skilled in the art to which it appertains to make and use the same.

This invention relates to improvements in that class of window shutting and opening devices wherein the shutters are actuated from within the house without opening the windows, and an object of the invention is to provide such a shutter actuating device which shall be simple and strong, and particularly free from cogs, gears, or other devices which are likely to become disarranged 20 easily.

A further object of the invention is to provide improved means for actuating the shutter opening and closing mechanism, said 25 means being neat and susceptible of use as a means for supporting adjustable shades.

A still further object of the invention is to provide shutter actuating means and a device for unlocking the shutter, that part of 30 the locking device which is within reach being inclosed within the shutter opening means.

A still further object of the invention is to provide an improved base upon which the 35 shutter actuating means is supported, this support being provided with automatic means for locking the shutter when the same has reached one of its extreme positions.

A still further object of the invention is to 40 provide improved means operable from within the house for opening and closing the slats of a shutter.

A still further object of the invention is to provide improved means for opening the 45 shutter when the shutter actuating means is moved, said improved means comprising a rigid member and a member slidably mounted upon the rigid member and operatively connected to the shutter actuating 50 device.

With these and other objects in view, the invention comprises certain novel constructions, combinations, and arrangements of parts as will be hereinafter more fully 55 described and claimed.

In the drawings, where two embodiments of the invention are as shown, and wherein similar reference characters designate corresponding parts: Figure 1 is a side elevation view of a window having the shutter actuating mechanism applied thereto. Fig. 2 is a perspective view of one end of the shutter showing the rigid actuating means secured thereto. Fig. 3 is a diagrammatic top plan view of the window actuating mechanism shown in Fig. 2. Fig. 4 is a perspective view of the window frame having applied thereto a modified form of my invention, one of the shutters being shown open and the other being shown in position to be 60 opened. Fig. 5 is a horizontal section taken through the upper part of part of the window looking upwardly. Fig. 6 is an enlarged detail of the bolt actuating means. Fig. 7 is a vertical section through the upper 65 part of the case showing the locking bolt. Fig. 8 is a perspective view of the lower support for the window shutter opening rod. Fig. 9 is a horizontal section showing improved means for actuating the slats of a 70 shutter. Fig. 10 is a detail perspective view showing one corner of a shutter and the locking catch and channel member secured thereto.

Generally, this invention aims to provide a 85 window shutter actuating means formed of a tube having a suitable actuating handle, this tube being connected to a shutter by means of a sliding contact so that the shutter will be open when the tube moves in the proper direction. In order to lock the shutter in one position, there is provided a bolt 90 which may be disposed to lock one or both of the shutters in ordinary window construction, this bolt being actuated by means of a rod located within the tube in the movement. The support for the tubular member may also be provided with inclined plane surface so as to automatically lock the shutter 95 in extended position. The sliding contact whereby the shutter is opened, preferably 100 comprises a rod upon which is slidably mounted a sleeve connected by suitable lever mechanism to the tube, although a roller and corresponding channel member may be 105 used for this purpose. In the accompanying description and drawings, both forms of the sliding contact are shown.

Referring to the drawings, 1 designates a 110 tubular member extending vertically for

practically the full length of the window frame, the lower end of the tube being rotatably mounted in a support and having secured thereto or formed integral therewith 5 a handle 3, while the upper end of the tubular member 1 is guided in a guide member 4. Extending from the upper end of the tubular member 1 is an arm 5, pivotally connected to a link 6, one end of which connects 10 with a short arm 7, of a lever 8 pivotally mounted in the top of the window frame. The lever 8, and the link 6 are made of comparatively thin material and are designed to pass through slots formed in the window 15 guides 9, formed in the usual form of window construction. The long arm 10 of the lever 8 has pivotally connected to the outer end thereof a sleeve 11, this sleeve 11 being adapted to slide back and forth upon 20 a rod 12 rigidly mounted between braces 13, braces 13 being secured in any suitable manner to the upper part of the shutter frame and preferably, though not necessarily upon the upper surface of the shutter when the 25 lower is in closed position.

Mounted within the tube 1 and adapted to move vertically therein is a lock actuating rod 14, the lower end of which is supported by the inwardly extending end 15 of a lever 30 handle 16 pivotally mounted by means of lugs 17 to the handle 3. By means of the lever handle 16, it will be seen that when the same is depressed, the rod 14 will be raised so as to move in a clockwise direction a bell crank 18, arm 19 of which has sliding contact with the rod 14. As shown in Fig. 6, the other arm 20 of the bell crank has pivotally connected thereto a rod 21, which is pivotally connected to an arm 22 35 secured in any manner to a pin 23.

As shown in Fig. 7, the rod of pin 23 has extending therefrom a trip arm 24, adapted to fit within the conic opening 25 of a lock bolt 26, it being understood that the particular showing herein is one of several expedients for the purpose of raising the bolt 26 when the rod 23 is rotated. Thus it will be seen, that as the lever handle 16 is depressed, the rod 14 will be raised and 40 the arm 22 rotated in a clockwise direction for the purpose of raising the bolt 26 by means of a trip arm 24 to the dotted line position indicated in Fig. 7.

As shown in Fig. 1, there is provided upon 45 each side of the window frame a tube 1, while there is provided only upon the right hand side the lock actuating rod 14. It is understood, of course, that if the rod 14 were placed upon the opposite side of the window 50 that the bell crank and arm 22 would move counterclockwise when the rod moved upwardly. The bolt 26 may be positioned to engage a catch 27, extending from the upper edge of one of the shutters such as 55 shown in Figs. 4 and 7, or the bolt 26 may

be received in a slot or bolt hole 28 formed in the upper edge of one of the shutters, as shown in Fig. 1.

The lower support 2 in which is rotatably mounted the tube 1, is composed of a brace 70 plate 29 which may be secured in any suitable manner to the casing of the window frame. Extending from the brace plate 29 is a boss 30, from which extends an inclined plane portion 31, the upper surface of which does not extend completely to the brace plate 29, but is cut away so as to form an opening 32 within which the pin 33 may fall when the handle 3 is thrown in a reversed position from that shown in Fig. 8. The pin 33 has extending upwardly therefrom arms 34 which carry a pintle 35 passing pivotally through the inwardly extending end 15 of the lever 16. By referring to Fig. 8, it will be seen that as the handle 3 is rotated to the position indicated in dotted lines, the pin 33 will ride upwardly upon the inclined surface 31, and thereby raise the end 15 to produce the corresponding upper movement of the rod 14, which will result in the operation already described. The end 15 is guided by the slot 36 formed in the lower end of the tubular member, while the sides of the U-shaped member formed by the arms 34 move within slots 37 formed on opposite sides of 90 the handle 3. After the pin 33 has passed beyond the end of the inclined surface 33, the weight of the rod 14 will force the same into the space 32, so that it will not be possible for the handle 3 to be moved until the 95 lever 16 is depressed. It is to be understood, of course, that the support just described can be provided with a pair of inclined plane portions 31, this duplicity of inclined plane portions making it possible 100 to lock the shutter in outer and inner positions by means of the pin 33 extending into the space 32.

From the description given, it will be seen that when it is desired to open one of the 110 shutters, it is necessary first to depress the handle lever 16 until the bolt 26 has been raised sufficiently to clear the catch 27, or to be entirely free from the bolt hole 28, after which the lever 3 is rotated in the desired direction, there being no necessity for keeping the lever handle 16 depressed after the blind has been started upon its outward swing. The outward swing of the shutter is accompanied by the rising of the pin 33 upon the 115 inclined plane portion 31, and it is designed to have the pin 33 enter the opening 32 just at the time when the shutter reaches the limit of its outer movement, the pin 33 serving to lock the shutter in this position as 120 previously described. When it is desired to close the shutter, it will be necessary to again depress the handle 16 until the pin 33 is entirely removed from the opening 32, at which 125 time the handle 3 is moved in a reverse di- 130

rection from the movement previously given it, the swing of the shutter being continued until the bolt 26, which is provided with a beveled portion 38, will be upon the catch 27. 5 If the upper edge of the shutter be provided with a bolt hole, suitable springs may be employed to return the bolt to position upon the descent of the rod 14.

As shown in Fig. 10, a modified form of 10 sliding contact may be used wherein the upper edge of the shutter is provided with a channel member 39, a lower edge of which is suitably secured to the shutter, this lower edge having extending therefrom a flange 15 40, and a back 41, the back 41 being of greater height than the flange 40, thereby defining an opening between the flange 40 and the cover 42 which extends from the back 41. It is preferable, though not necessary, to have the cover 41 extend slightly 20 beyond the flange 40 so as to prevent ingress of rain, snow, etc., from interfering with the action of the roller 43'. In the modified frame, this roller 43' takes the place of a 25 sleeve 11, the roller being rotatably mounted upon the outer end of the long arm 10 of the lever 8, and pressing against the back 41 when the tube 1 is turned to open the shutter.

30 In order to adjust the slats of the shutter from within the room, there is rotatably mounted within one or both sides of the casting of the window frame a rod 43 provided with a suitable handle 44, and having a trip 35 arm 45 adapted to enter an opening 46 cut within a hinged end of the shutter frame. One of the slats has an elongated pivot 47, having extending at right angles therefrom a trip arm 48, adapted to engage arm 45. 40 When it is desired to move the slats, the handle 44 will be turned until the arm 45 has loosely engaged trip arm 48, when it will be merely necessary to turn the handle so that the arm 45 will rotate the trip and open the 45 slats, in view of the fact that the arm 45 is not secured in any way to the trip 48, but merely engages the same loosely. In order that all the slats may move in unison, there is provided a master-rod 49, as shown in Fig. 7, 50 which moves all of the slats when any one slat is moved, this construction being common in window blinds or shutters. When it is desired to reverse the movement of the slats it will be necessary to withdraw the rod 43 until the arm 44 can be rotated in the 55 opening 46 without engagement with the trip 48, this operation being made possible by so constructing the rod 43 that the same can slide longitudinally of the window frame. 60 When the arm 45 has been moved clear of the trip 48, the rod 43 is again pushed inwardly in the handle 44 rotated in a reversed direction, at which time the slats will be actuated.

65 In the preferred form of the invention as

shown in Fig. 1, when it is desired to apply the invention to a window already constructed, it will be necessary simply to cut out a small portion in the upper part of the sash, but insomuch as this cut-out portion will be 70 small and in a protected position, no disfigurement of the window will result, nor will it be possible for snow, rain, etc., to beat through the opening.

While the hinges of the shutter have been 75 shown as admitting of no vertical sliding movement when the shutter assumes its uppermost position, yet it is to be understood that the long end 10 of the lever 8 will be made sufficiently flexible to allow the usual 80 hinges used in shutter construction to be used in conjunction with the invention. By having the actuating rod 14 incased within the tube 1, the actuating means are made to 85 present a pleasing appearance and also afford means for supporting such fixtures or attachments as are usually applied to windows, it being further noted that the operating parts are out of reach.

90 I claim:

1. A window shutter opening device comprising a tubular member adapted to open the shutter, a rod movably mounted within the tube, and a shutter lock operatively connected to the rod and adapted to unlock as 95 the rod moves in a predetermined position.

2. A window shutter opening device comprising a tubular member adapted to open a shutter, a rod reciprocally mounted within the tubular member, means carried by the 100 tubular member for reciprocating the rod, and a shutter lock operatively connected to the rod and adapted to release the shutter when the rod is moved in a predetermined 105 position.

3. A window shutter opening device comprising a tubular member adapted to open a shutter as the same rotates, a handle for rotating the tubular member, a rod reciprocally mounted within the tubular member, 110 a rod actuating means forming part of the handle and pivoted thereto, and a shutter releasing means operatively connected to and actuated by the rod.

4. A window shutter opening device comprising a tubular member adapted to open the shutter, a rod reciprocally mounted within the tubular member, means locking the shutter adapted to be actuated to release the window when the rod moves in a predetermined direction, and a rod actuating lever pivotally mounted with respect to the tubular member and having an arm extending within the said tubular member and engaging one end of the rod. 115 120 125

5. The combination in a shutter opening device, of a rod slidably mounted in a tubular member, the rod adapted to unlock the shutter and the tubular member adapted to open the shutter. 130

6. The combination in a shutter opening device, of a tubular member adapted to open the shutter, a rod slidably mounted within the tubular member, a pin moving with the rod, and a support carrying the tubular member provided with an opening positioned to receive the pin to prevent the turning of the tubular member.
7. The combination in a shutter closing and opening device, of a tubular member adapted to open the shutter, means for locking the shutter in one position, a rod slidably mounted in the tube adapted to unlock the shutter from said position, a lever pivotally mounted with respect to the tubular member, a pin depending from the lever, and

an inclined plane adapted to engage the pin, the plane terminating in a slot adapted to receive the pin to lock the shutter in a second position.

8. The combination in a shutter opening and closing device, of a tubular member, a rigid member slidably mounted within the tubular member, one of said members adapted to unlock the shutter and the other member adapted to open the shutter.

In testimony whereof I affix my signature in presence of two witnesses.

GEORGE W. LANCASTER.
